UNITED STATES PATENT OFFICE.

STANLEY C. BRYANT, OF CHICAGO, ILLINOIS.

ELECTRIC-CIRCUIT CONTROLLER.

Application filed August 6, 1921. Serial No. 490,398.

To all whom it may concern:

Be it known that I, STANLEY C. BRYANT, a citizen of the United States, and a resident of Chicago, in the county of Cook and State 5 of Illinois, have invented certain new and useful Improvements in Electric-Circuit Controllers, of which the following is a specification, reference being had to the accompanying drawing.

10 My invention relates to electric circuit controllers of the type known as flashers, used to control signs or signals which are periodically illuminated at short intervals, or in other words are caused to flash. In 15 the operation of such signals it is desirable that the illumination of the signals be maintained for a short length of time, as distinguished from an instantaneous flash, and it is also necessary that the circuit controlling 20 device by which such signals are operated be entirely automatic in operation, as it is impracticable to inspect them frequently. This is particularly true of signals of this character which are installed in city streets 25 or on country roads, as the expense of maintaining such signals would be prohibitive if much attention were required to keep them in successful operation. To provide a signal which will meet the requirements of 30 such use is the principal object of my present invention, but I wish it to be understood that while my improved apparatus is designed primarily for the purpose stated, it is also well adapted for use in many other situations, and, therefore, I do not restrict myself to its use for any particular purpose. The nature of my invention will appear 35 from the following description thereof in connection with the accompanying drawings 40 which illustrate one form in which it may be embodied. What I regard as new is set forth in the claims.

In the accompanying drawings,—

Fig. 1 is a side elevation of my improved 45 apparatus, some parts being broken away; and

Fig. 2 is a diagrammatic view showing the arrangement of the circuits when the controlling device is used in connection with 50 a signal lamp such as are commonly employed for street signals.

In the embodiment of my invention illustrated I employ a main electromagnet 3 which is of the slow releasing type. This 55 magnet is shown as having its poles 4 fitted

in a supporting standard 5 rising from a base 6 which is mounted on a block 7. The standard 5 is inclined somewhat from the vertical so that the armature hereinafter described will tend to move away from the 60 poles 4 by gravity. Cooperating with the magnet 3 is an armature 8, in the form of a bar of suitable magnetic material, which is arranged in an approximately upright position, its lower end being rounded and having a rocker bearing in a block 9 preferably secured to the standard 5. This rocker bearing is formed by providing a rounded recess in the upper face of the block 9 and correspondingly rounding the lower end of the 65 armature, as shown at 10 in Fig. 1. The armature is held loosely in engagement with its bearing by a screw 11 which is passed through the upper portion of the block 9 and through a hole 12 in the armature in 70 which it fits loosely so as not to interfere with the rocking of the armature. As shown in Fig. 1, the screw 11 is inserted from the side of the block 9 next to the standard 5 so that it cannot work loose. This form of 75 bearing is particularly advantageous in a device of this character because it does not require lubrication, and there is no appreciable wear so that it requires no attention.

When the armature 8 is in its normal position its upper end is somewhat farther away than its lower end from the magnet 3 so that when the magnet is energized the armature is caused to rock toward the poles 80 of the magnet. For limiting the extent to 85 which the upper end of the armature can approach the magnet, and also for adjusting the action of the apparatus, as will be hereinafter described, the armature is provided with an adjustable screw 13 of brass, or other non-magnetic material, which extends through the armature and is adapted to strike the upper pole of the magnet when the armature reaches the desired limit of its movement in that direction. The screw 13 90 is provided with a lock nut 14 for holding it in position when adjusted. The armature 5 also carries a spring contact member 15 95 preferably secured to its upper end, as shown in Fig. 1. The purpose of this contact member will be explained later.

Carried by the armature 8 is an auxiliary electromagnet 16 which is arranged to rock relatively to the armature 8, which serves 100 as an armature for the auxiliary magnet 110

also. The magnet 16 is provided at its lower end with a stud 17 rounded at its lower end and fitted in a rounded bearing in a block 18 secured to the lower end portion 5 of the armature 8, the arrangement of these parts being similar to the mounting of the armature 8. The auxiliary magnet 16 is provided with a pole piece 19 bent at right angles so as to lie adjacent to the upper 10 portion of the armature 8. A pin 20 of brass or other non-magnetic material is secured to the pole piece 19 and extends through a passage in the armature 8 to a point somewhat beyond the inner face of 15 said armature, so that it is adapted to strike the standard 5 when the armature 8 approaches the limit of its movement under the influence of the magnet 3, and thereby mechanically separate the pole 19 of the 20 auxiliary magnet 16 from the armature 8, the purpose of which action will be herein-after set forth.

21 indicates a spring contact which is secured to a block 22 carried by the auxiliary magnet 16 and extends into position to be engaged by contact 15 when the parts are in the position shown in Fig. 1. When, however, the pole-piece 19 of the auxiliary magnet is moved away from the armature 8 30 through the instrumentality of the rod 20 the contacts 15 and 21 are separated. These contacts, therefore, serve as a switch which, as will be herein-after described, opens and closes the circuit through the coils of the 35 main magnet 3 and auxiliary magnet 16. Adjacent to the auxiliary magnet 16 is a standard 23 which carries an adjusting screw 24 having at its inner end a stop 25 of non-conducting material adapted to be engaged 40 by the spring contact 21 when the latter is in its initial position shown in Fig. 1.

In Fig. 2, I have shown my improved circuit controlling device as used for controlling the flashing of a lamp 26 which is provided with a normal light filament 27 and a reserve light filament 28, the latter being arranged to be automatically put in service if the normal filament should be broken or burn out. The flow of current to the lamp 50 26 is controlled by a relay 29 comprising a core 30 having a winding 31, a pole 32, and an armature 33 which is pivoted so as to swing toward and from the pole 32. The armature 33 is preferably mounted in the 55 same manner as the armature 8, that is to say, on a rocking bearing. The armature 33 is adapted to bridge two contacts 34, 35 when the circuit through the normal light filament is broken, under which condition 60 the coil 29 will be out of circuit and the core 30 will not be energized. When, however, the normal light filament is intact the current will flow through the coil 29, thereby energizing the core 30 and moving the armature 33 up against gravity out of contact

with contact point 35, which, as herein-after described, will cut off current from the reserve light filament 28.

In the drawings I have shown a battery 26 as the source of current, but the necessary 70 current may be derived from any other suitable source. In the diagrammatic illustration of Fig. 2 the battery is connected by a wire 37 with the coil 38 of auxiliary electromagnet 16, the opposite end of which coil 75 is connected by a wire 39 with spring contact 21. The opposite side of the battery is connected by a wire 40 with one end of the coil 41 of the main electromagnet 3, and also by a wire 42 with the coil 31 of the relay magnet 29. The opposite end of the latter coil is connected by a wire 43 with a terminal 44 of the lamp 26 which leads to the filament 27. The corresponding terminal 45 of the lamp which leads to filament 28 is connected 80 by a wire 46 which leads to contact point 35. Contact point 34 of the relay 29 is connected by a wire 47 with the wire 42. A wire 48 leads from a terminal 49 of the lamp which is connected with the other ends of 90 the filaments 27, 28, and is connected with the armature 8 and also with the other end of the coil 41 of the main magnet 3.

The operation of the apparatus is as follows: The initial position of the armature 95 8 and the parts carried thereby is shown in Fig. 1, which position they assume under the action of gravity when the electromagnet 3 is deenergized. At the instant that the parts assume such position, however, that is to say, when the contact member 15 comes into contact with the contact member 21, the main electromagnet 3 is energized by the circuit thereby established, which goes from the battery through the coil of auxiliary electromagnet 16, thence through spring contacts 21 and 15 and armature 8 to the coil 41 of the main magnet. The circuit through such coil is completed by wire 40. At the same time a portion of the current passing 100 through the coil 41 is conducted through the coil 31 of the light relay 29, thereby energizing the core thereof and lifting the armature 33 out of contact with contact point 35. This is on the assumption that the filament 27 is intact. If, however, such filament be 105 broken the core 30 will not be energized, and in that case the current will flow through the armature 33 by wire 46 to the reserve light filament 28 and thence back by wire 48 to 110 coil 41.

The flow of current through the coil of auxiliary electromagnet 16 will energize the pole 19 thereof, which will accordingly be 115 attracted to the armature 8, and, therefore, when said armature moves toward the poles 4 of the main electromagnet under the influence of the attraction thereof, the auxiliary magnet 16 with the spring contact 21 attached to it will move with said armature 120

ture. The parts carried by the armature 8 will, therefore, retain their initial relative position until the pin 20 strikes the standard 5, which occurs shortly before the armature 8 reaches the limit of its movement toward the poles 4. When the pin 20 strikes the standard 5 it will arrest the auxiliary magnet 16, but the armature 8 will continue to move toward the poles 4, thereby separating the auxiliary magnet pole 19 from the armature 8 and at the same time breaking contact between the switch members 21 and 15. The auxiliary magnet 16 will thereupon drop back to its initial position 15 with the spring contact 21 resting against the stop 25. The separation of the spring contacts 21 and 15 will break the circuit through the main magnet 3, as well as through the auxiliary magnet 16, and, therefore, the armature 8 will be slowly released 20 by the main magnet 3 and will then drop back to its initial position, which restores contact between spring contacts 21 and 15, and again establishes the circuit through the main magnet. The operation above described will thereupon be repeated and will continue as long as current is supplied by the battery or other source.

It will be apparent that the time between 30 flashes, as well as the duration of the flash, may be regulated by means of the adjusting screws 13 and 24, but when these have been set in the desired position the apparatus requires no further attention but will 35 continue to operate indefinitely so long as current is supplied or both filaments of the lamp are not destroyed. Even if the lamp should not be operative the circuit controlling device will continue to operate as the 40 circuits controlling the operation of such device are not dependent upon the lamp.

As will be understood from the foregoing description, the circuit through the main magnet is not broken until the armature 8 approaches the poles of said magnet, and consequently the light continues to burn during an appreciable interval of time. Also the slow release feature of the main magnet prevents instantaneous return of the 45 armature 8 to its initial position after the circuit through the main magnet is broken, and consequently there is also an appreciable interval of darkness before the contact 50 15 again comes into contact with contact member 21 and re-establishes the light circuit as well as that through the main magnet. With this apparatus, therefore, a very slow rhythmic contact is made which gives the desired slow flashing effect to the lamp.

55 60 In addition to the principal feature of my invention above described, I wish to call attention to several other advantages which result from the construction shown and described. One of these is that as the movable parts return to their position by grav-

ity only, the use of springs is avoided and there is less danger of any of the parts getting out of order. Also the stationary parts are mounted so that they are held rigidly and permanently in position, and, therefore, 70 the movable parts cooperating therewith are not apt to get out of adjustment. In constructing the main magnet 3 I prefer to use a simple U-shaped core to avoid any losses that might occur if two cores and a 75 connecting yoke of the usual type were employed.

So far as I am aware I am the first in the art to provide an electric circuit controlling device having an electromagnet and a movable armature therefor, in connection with a switch which controls the circuit through said magnet and is arranged to maintain the circuit through the magnet for a time after the armature is moved from its initial position, and also to break the circuit through said magnet an appreciable length of time before the armature returns to its initial position. My invention is therefore generic 80 in character, and the claims hereinafter 85 made are to be construed accordingly.

What I claim as my invention and desire to secure by Letters Patent, is—

1. An electric circuit controller comprising a main electromagnet, a movable armature therefor actuated by the energization thereof, an auxiliary electromagnet adapted to magnetically engage and move with said armature, a switch comprising members carried by said armature and said auxiliary 95 electromagnet, the members of said switch being arranged to make contact with each other when said armature and said auxiliary magnet are in their initial position and to maintain such contact until the armature 100 reaches a predetermined position under the influence of said main electromagnet, and means for then opening said switch.

2. An electric circuit controller comprising a main electromagnet, a movable armature therefor actuated by the energization thereof, an auxiliary electromagnet adapted to magnetically engage and move with said armature, a switch comprising members carried by said armature and said auxiliary 110 electromagnet, the members of said switch being arranged to make contact with each other when said armature and said auxiliary magnet are in their initial position and to maintain such contact until the armature 115 reaches a predetermined position under the influence of said main electromagnet, and a pin carried by said auxiliary magnet and operating to mechanically separate the members of said switch when the armature 120 reaches a predetermined position.

3. An electric circuit controller comprising an electromagnet, an armature therefor adapted to swing away from the poles of said magnet by gravity when said magnet 130

is deenergized, an auxiliary electromagnet carried by said armature and having a pole adapted to magnetically engage said armature, the pole of said auxiliary magnet being adapted to swing away from said armature by gravity, means for moving the pole of said auxiliary magnet out of engagement with said armature when the latter reaches a predetermined position under the influence of said main electromagnet, and switch

members carried by said armature and by said auxiliary electromagnet, said switch members being arranged to be in operative contact with each other when the pole of said auxiliary magnet engages said armature, and to be separated from each other when said pole is disengaged from said armature. 15

STANLEY C. BRYANT.
